CLAIM

The ornamental design for container with top opening, as shown and described.

DESCRIPTION

FIG. 1 is a front, perspective view of a container with top opening in accordance with the present invention;

FIG. 2 is a side elevation, in section of the container with top opening, taken along line 2—2, of FIG. 1;

FIG. 3 is a top plan view of the container with top opening of FIG. 1;

FIG. 4 is a bottom plan view of the container with top opening of FIG. 1;

FIG. 5 is a rear side view of the container with top opening of FIG. 1;

FIG. 6 is a front view of the container with top opening of FIG. 1;

FIG. 7 is a side view of the container with top opening of FIG. 1;

FIG. 8 is another side view of the container with top opening;

FIG. 9 is a perspective view of the container with top opening, according to another embodiment of the invention;

FIG. 10 is a top plan view thereof;

FIG. 11 is a bottom plan view thereof;

FIG. 12 is a perspective view of the container with top opening according to still another embodiment of the invention

FIG. 13 is a top plan view thereof; and,

FIG. 14 is a bottom plan view thereof.
